US00D796684S

(12) **United States Design Patent** (10) **Patent No.:** **US D796,684 S**
(45) **Date of Patent:** **** Sep. 5, 2017**

(54) **WOUND DRESSING**

(71) **Applicant:** **BIO-MEDICAL CARBON TECHNOLOGY CO., LTD.**, Taichung (TW)

(72) **Inventors:** **Tse-Hao Ko**, Taipei (TW); **Jui-Hsiang Lin**, Taichung (TW); **Pei-Hsun Chou**, Taichung (TW); **Yen-Ju Su**, Taichung (TW); **Wei-Shan Hsu**, Taichung (TW)

(73) **Assignee:** **BIO-MEDICAL CARBON TECHNOLOGY CO., LTD.**, Taichung (TW)

(**) **Term:** **14 Years**

(21) **Appl. No.:** **29/485,340**

(22) **Filed:** **Mar. 18, 2014**

(51) **LOC (10) Cl.** **24-04**

(52) **U.S. Cl.**

USPC **D24/189**

(58) **Field of Classification Search**

USPC D24/189, 190-192; D16/101

CPC A61F 13/00021; A61F 13/0203; A61F

13/066; A61F 13/00063; A61L 15/26;

A61L 27/52

CLAIM

The ornamental design for the wound dressing, as shown and described.

DESCRIPTION

FIG. 1 shows a perspective view of the first embodiment of the present design.

FIG. 2 shows a front view of the first embodiment of the present design.

FIG. 3 shows a right view of the first embodiment of the present design.

FIG. 4 shows a top view of the first embodiment of the present design.

FIG. 5 shows a perspective view of the second embodiment of the present design.

FIG. 6 shows a front view of the second embodiment of the present design.

FIG. 7 shows a right view of the second embodiment of the present design; and,

FIG. 8 shows a top view of the second embodiment of the present design.

1 Claim, 4 Drawing Sheets
